PANEL FOR FURNITURE

Richard M. Chapin, Charlotte, N.C., assignor to Dolly
Madison Industries, Huntingburg, Ind.

Filed Jan. 7, 1972, Ser. No. 216,334

Term of patent 7 years

Int. Cl. D6—06

U.S. Cl. D6—192

FIG-1

FIG-2

FIG. 1 is a perspective view of a panel for furniture showing my new design; and

FIG. 2 is a perspective view of a panel for furniture showing a modified form of my new design.

The reverse sides of the panels shown in the drawings are substantially plain and unornamented.

I claim:

The ornamental design for panel for furniture, substantially as shown and described.
